United States Patent Office

Des. 228,220
Patented Aug. 28, 1973

228,220

BEVERAGE GLASS OR SIMILAR ARTICLE

Walter B. Achenbach, Toledo, Ohio, assignor to Owens-Illinois, Inc., Toledo, Ohio

Filed Sept. 2, 1971, Ser. No. 177,525

Term of patent 14 years

The portion of the term of the patent subsequent to
Aug. 28, 1987, has been disclaimed

Int. Cl. D7—01

U.S. Cl. D7—15

FIG. 1 is a top plan view of a beverage glass or similar article showing my new design.

FIG. 2 is an elevational view thereof.

FIG. 3 is a central sectional view taken along and in the direction of the sectional plane 3—3 designated in FIG. 1.

I claim:

The ornamental design for a beverage glass or similar article, as shown.
